UNITED STATES PATENT OFFICE.

VINCEN P. McVOY, OF MOBILE, ALABAMA.

COMBINED CYLINDER COCK AND RELIEF VALVE.

Application filed July 3, 1920. Serial No. 393,890.

This invention relates to certain new and useful improvements in cylinder cock and relief valve combined, having for its objects among others to provide a simple and efficient device of this character composed of few parts, those readily assembled, capable of manufacture at small cost, reliable in its action and not liable to get out of order.

A further object of the invention is to provide a spring pressed piston and also a spring-pressed relief valve cooperatively arranged to operate in one direction, and in the opposite direction movable independently of each other or together according to the condition of use.

Other objects and advantages of the invention will hereinafter appear and the novel features thereof will be particularly pointed out in the appended claims.

20 The invention, in its preferred form, is clearly illustrated in the accompanying drawing, which, with the numerals of reference marked thereon, form a part of this specification, and in which—

25 Figure 1 is a substantially central longitudinal section showing my present improvement applied to a cylinder.

Figure 2 is a similar view showing the parts in different position.

30 Like numerals of reference indicate like parts throughout the different views.

Referring to the drawings, 1 designates a portion of an engine cylinder to which my present improvement is shown as applied by screwing the threaded portion 2 thereof into the bottom of the cylinder. This portion 2 extends laterally from the body portion 3 which is shown as provided with a nipple 4 screw-threaded, as 35 shown at 5, and adapted to receive the threaded portion 6 of a cap nut 7.

8 is a bridge or partition having an aperture 9 therein for the reception of the guide member 10 projecting from the check valve 11, the barrel 12 of which is received within the bore 13 of a piston 14, which latter is adapted to reciprocate in the cylindrical portion 15 of the body 3. The end of the portion 15 is screw-threaded, as at 16, to receive the threaded portion 17 of a cap 18. The cap 18 has the opening 19 therein and with this opening communicates the bore of the screw-threaded portion 20 with which is adapted to be connected an air pipe, not shown, for the purpose of supplying air to the interior of the cylinder 15.

It is to be understood that the air pipe is designed for connection with a suitable reservoir or other suitable source of supply of air under pressure and provided with a manually operated controlling valve, but it is not thought necessary to show such reservoir or connections between the same and the cap 18.

Within the bore of the piston 14 is a spring 21, one end of which is seated against the adjacent end of the barrel 12, while 22 is a spring disposed between the cap nut 7 and the adjacent end of the guide member 10 of the check valve, as clearly shown in both views.

The piston 14 is guided upon the barrel 12 and, in turn, serves as a guide for the latter, the said piston being provided with a seat portion 23 adapted to be seated against a seat 24 surrounding the opening 25, as shown.

26 is a lateral discharge outlet from the portion 27 of the body.

With the parts constructed and arranged substantially as hereinbefore described and connected up with the engine cylinder, as shown, the operation, briefly stated, is as follows:—

As shown in Figure 1, the parts are in their closed position, air pressure being upon the end of the piston 14, which latter is forced to its seat at 24; the check valve 11 is also forced to its seat, the spring 21 being put under compression of sufficient strength to overcome cylinder pressure under all normal conditions. Under these same conditions, with the parts in the position shown in Figure 1, should the engine pick up water from the boiler, or, in case of an accumulation of steam sufficient to overcome the tension of the spring 21, the check valve 11 will be unseated and moved against the tension of the spring 21, allowing the water or steam to exhaust through the connection 2, chamber 27 and the outlet 26 to the atmosphere, through the opening 9 in the partition 8. Any pressure over and above throttle pressure, upon the area of the check valve 11 will serve to unseat the same. As soon as pressure is reduced to normal, the spring 21 forces the check valve again to its seat, as shown in Figure 1.

Figure 2 shows the condition and position of the parts when the air is released from the chamber back of the piston 14. When this pressure is released, the spring 22 serves

to force the check valve and its barrel to open position, being assisted by the pressure or condensation from the cylinder through the port 2, chamber 27, valve port 9 and out let passage 26. As soon as the air pressure is released, the spring 21 serves to force the piston 14 to its limit, and, hence, the spring 21 does not offer any resistance to the unseating of the check valve, to the extent shown in Figure 2. When air is admitted through the bore 20 and port 19, the piston 14 is moved to the right in the drawing, the spring 21 is compressed and the check valve 11 is forced to its seat, and then the seat portion 23 of the piston is brought against the seat 24 so as to positively prevent leakage of air which would be detrimental to the storage of air on the engine which has to be conserved for brake pressure.

It is to be understood that in the movement of the parts from the position in which they are shown in Figure 2 to that in which they are shown in Figure 1 (when air is supplied to the chamber 28 through the opening 19), the check valve 11 is first forced to its seat by the spring 21, in advance of the seating of the piston 14 against its seat, the spring 22 being a comparatively light spring, while the air acting upon the position at its larger area has to compress the spring 21, transmitting the load thereof to the check valve against its seat.

Modifications in details may be resorted to without departing from the spirit of the invention or sacrificing any of its advantages.

What is claimed as new is:

1. A combined cylinder cock and relief valve embodying an air cylinder, a piston having a seat portion, a check valve movable to seating position by and in advance of said piston, adjacent seats for the piston and valve, and springs at opposite ends of the said valve, said seats being disposed between said springs.
2. A combined cylinder cock and relief valve embodying an air cylinder, a bored piston therein having a seat portion, a check valve supported in and movable to seating position in advance of the piston, adjacent seats for the piston seat portion and the

check valve, a spring acting on the piston and disposed between the stem of the valve and the end wall of the bore of the piston, and a spring acting on the valve to hold the same in seated position when air pressure is released from the piston.

3. A combined cylinder cock and relief valve embodying an air cylinder, a bored piston therein having a seat portion, a check valve supported in and movable to seating position in advance of the piston, adjacent seats for the piston seat portion and the check valve, a spring acting on the piston and disposed between the stem of the valve and the end wall of the bore of the piston, and a spring acting on the valve to hold the same in unseated position when air pressure is released from the piston, said springs acting upon opposite ends of the check valve.

4. A combined cylinder cock and relief valve embodying an air chamber, a bored piston therein having a seat portion, a check valve supported in and movable to seating position in advance of the piston, adjacent seats for the piston seat portion and the check valve, a spring acting on the piston and disposed between the stem of the valve and the end wall of the bore of the piston, and a spring acting on the valve to hold the same in unseated position when air pressure is released from the piston, the said springs being of different power.

5. A combined cylinder cock and relief valve comprising a body portion with a bridge having an opening therethrough and a seat for a piston, a relief valve, an air cylinder, a bored piston in said cylinder adapted to cooperate with said seat to prevent leakage of air, a spring in the piston acting on one end of the valve, and a spring acting on the opposite end of the valve, one of the springs being seated in the bore of the piston and said springs being of different power, the cylinder having a lateral discharge outlet and the seats for the piston and valve being disposed on opposite side walls of said outlet.

In testimony whereof I affix my signature.

VINCEN P. McVOY.
